(57) **CLAIM**

The ornamental design for a medical thermometer, as shown and described.

DESCRIPTION

9.1 Perspective (front, top, left)

9.2 Perspective (bottom, back, left)

9.3 Front

9.4 Back

9.5 Left

9.6 Top

9.7 Bottom

The right-side view is omitted because it is a mirror image of the left-side view; the white overlay delineated with broken lines depicts portions of the medical thermometer that forms no part of the claimed design.
